METHOD AND APPARATUS FOR REDUCING
ECHO EFFECTS IN PICTURE TRANSMIS-
SION SYSTEMSFrank J. Bingley, Chestnut Hill, Pa., assignor to

adelphie, Pa., a corporation of Delaware

Application March 19, 1942, Serial No. 435,402

28 Claims. (Cl. 178—7.1)

This invention relates to picture transmission systems and the like, and to a method and means for substantially reducing or eliminating the effects of echo signals on the received or reconstituted picture. More particularly, the invention relates to television systems of the alternate carrier type, and to a method and means for reducing or substantially eliminating certain undesirable effects resulting from the arrival, during the picture line periods, of echoes of the horizontal, or line, synchronizing signals.

One of the problems encountered in picture or television transmission, and one that obtains with any type of modulation, is that which results from the reception of long-delayed echoes, corresponding to signal path differences of the order of a mile or several miles. Since the speed of propagation of a radio wave is approximately 1,000 feet per microsecond, a path difference of say 3 or 4 miles, as between the direct and the reflected signal path, may produce echoes delayed by 15 or 20 microseconds. In magnitude these echoes may be relatively faint due to the greater path length, to the fact that the echo-signal normally suffers considerable attenuation in reflection, and to the fact that the indirect path is usually closer to the earth than is the direct path. On the other hand, since the blanking, and particularly the synchronizing signals, are of greater amplitude than the line or picture portion of the signal, reflected blanking and synchronizing signals of considerable strength sometimes appear in the picture as a result of these long-delayed echoes. Because of the inherently greater effectiveness of the synchronizing signals in alternate carrier television systems, unusually strong echoes of the synchronizing signals may sometimes be received. This invention is particularly directed to the elimination or reduction of echo effects in this type of system.

In general, an echo may appear in a television picture by combining or beating with the picture carrier. Thus the echo may add to or subtract from the picture carrier depending upon the particular phase relation existing between the two signals at a given instant. This phase relation depends (except for changes effected at the transmitter itself) upon the difference in path length between the direct and reflected signals; and the only way in which this difference can be appreciably varied, assuming that the transmitting and receiving antennas are fixed, is by a variation in the placement of the reflector causing the echo. But since the reflector is usually a high building, bridge, gas tank, hill, or similar ob-

ject, it too can be regarded as a substantially fixed structure, and hence in any given installation, the echo signal, as it appears upon the viewing screen at the receiver, is subject only to such phase relations between the direct and reflected signals as may result from periodic phase changes effected within the transmitter itself.

In the copending joint application of Frank J. Bingley and William E. Bradley, Serial No. 433-10 660, filed March 6, 1942, an echo reduction system was described, by means of which the deleterious effects of echo signals could be substantially reduced or eliminated by providing a phase-changing means at the transmitter for periodically changing the "polarity" of the echoes seen at the receiver, so that they are of opposite characteristics in successive frames. In one form of the invention, this was accomplished by periodically changing the phase of the synchronizing signal carrier with respect to the video carrier, these changes being so timed that the successive echoes tend to balance each other out so far as their impression upon the observer is concerned. The phase changes, or reversals, described in 20 the above-mentioned joint application, are effected in a time which is generally short compared to the duration of the synchronizing or blanking signals. To this end the phase changing or reversing means shown in the said joint application is adapted to effect substantially instantaneous changes in phase.

According to the present invention, phase reversals are effected gradually, and by quite different means—namely by selecting video and 35 synchronizing carrier frequencies which bear a numerical relation to each other such that the phase of the beat frequency (i. e. the echo) resulting from the mixing of the video carrier and a delayed synchronizing signal carrier, is substantially opposite (differs by 180 degrees) in successive frames. The phase changes referred to are effected at the transmitting station and require no additional equipment at the point of reception.

45 It is a principal object of this invention to provide a method and a means for substantially eliminating certain echo effects which may be encountered in television transmission systems of the alternate carrier type.

Another object of the invention is to provide a method and means for transmitting a television signal, or the like, which when received will produce a picture which is substantially free of echoes of the synchronizing signals.

50 Still another object of the invention is to pro-

vide means for eliminating certain of the spurious images produced when television signals are received by way of two or more transmission paths.

A further object of the invention is to provide a method and means by which the relative phase of echo signals may be gradually advanced, retarded, or otherwise changed, the phase changes progressing at such a rate that echo images of substantially opposite characteristics are received in successive frames.

These and other objects and features of the invention will be apparent from the following description and the accompanying drawings, in which:

Fig. 1 shows a typical disposition of transmitter, receiver, and reflecting structure, which may give rise to objectionable echo signals;

Fig. 2 is an explanatory diagram illustrating certain characteristics of typical echo patterns;

Fig. 3 is illustrative of one of the methods employed to effect cancellation of echo patterns; and

Fig. 4 is a partially schematic and partially diagrammatic representation of an alternate carrier television system embodying the present invention.

The present invention may best be understood by considering first the causes of echo signals, and their appearance when viewed on the screen of the picture tube. A typical condition which may give rise to objectionable echoes is illustrated in Fig. 1. In this figure, a television receiver R is represented as being 12 miles distant from a transmitting station T. At distances of 6 and 10 miles from the transmitter and receiver, respectively, is a wave reflecting structure such as a tall building, a water tower, a steel bridge, or the like. Taking the speed of a radio wave as about one-fifth mile per microsecond, it will be apparent that the time required for the signal to traverse the direct 12-mile path between the transmitter and receiver will be about 60 microseconds, while the time required for the reflected signal to traverse the indirect 16-mile path will be about 80 microseconds. Consequently, the reflected wave, i. e., the echo, will arrive at the receiver about 20 microseconds behind the direct wave. This may be regarded as illustrative of a simple echo, as differentiated from multiple echoes which arise when a plurality of reflecting structures provide a plurality of indirect signal paths of different length.

Fig. 2 is an explanatory diagram in which the time and amplitude characteristics of a typical television signal S are related to the screen P of a conventional television picture tube. The television signal, in accordance with the present practice, may comprise synchronizing pulses S_a of approximately 5.1 microseconds duration, blanking pulses S_b of approximately 10.2 microseconds, and a line or video period S_c of approximately 53.3 microseconds. These are substantially the specifications employed in a conventional 525-line interlaced television system, with 30 frames (60 fields) per second. Since the line period corresponds to the time required for the electron beam in the picture tube to trace one line across the picture tube screen, the width of the screen P has, for convenience, been made equal in length to the line portion of the television signal S. As is conventional, the amplitude of the blanking pulses S_b may be regarded as corresponding to a "black" signal level, zero car-

rier as corresponding to a very bright signal level, while the synchronizing pulses may be regarded as corresponding to a blacker-than-black or "infra-black" signal level. The video signal existing during the 53.3 second line period has, for the purpose of this description, been established at a level midway between zero carrier and the black level, and will correspond approximately, therefore, to a gray level.

When a signal of these characteristics is received without an attendant echo, there will be reproduced, upon the screen of the picture tube, a line similar to that shown (with exaggerated width) at A in Fig. 2, and having a uniform grayish appearance, the latter being indicated in the drawing by the closely spaced dots. This uniform appearance will be destroyed, however, if one or more echo signals is received along with the desired direct signal. Strictly speaking, under these conditions, the appearance of the entire line will be affected, but in general echoes of the video portion of the signal can, by reason of their lesser amplitude, be ignored, and, consequently, for most practical purposes only those echoes produced by the higher amplitude blanking and synchronizing pulses need be considered. Of these pulses, the latter are, of course, the more important by reason of their greater amplitude.

Line B in Fig. 2 is illustrative of the normal appearance of a picture line when receiving a strong echo signal. This may be regarded as representing the case of a common carrier system where the video and synchronizing intelligence is transmitted at the same carrier frequency. However, as will be explained in greater detail hereinafter, line B (as well as line C) is also illustrative of the appearance of an echo in an alternate carrier system where the difference between the synchronizing signal carrier and the video carrier is very small. The echo illustrated resembles those which are produced by the delayed reception of the blanking and synchronizing signal, and is displaced from the left-hand edge of the screen P by a distance which is proportional to the time interval between the arrival of the signal traveling the direct path and the arrival of the signal traveling the indirect or reflected path. If the difference in length between these paths is small, the echo will be reproduced at or near the left-hand edge of the screen, whereas greater path differences cause the echo to appear further to the right. Of course, where the path difference is very great, the attenuation suffered by the reflected signal is usually so considerable that the echo is too weak to be noticeable.

As is indicated in the drawing, the echo shown in line B is produced by the arrival of blanking and synchronizing pulses during the line or video period S_c. Specifically, this echo is produced by the arrival of the pulses S_a, S_b, by way of an indirect path, approximately 20 microseconds after the reception of these pulses by way of the direct path. The echo signal produces on the screen P an echo pattern whose width is equal to the width of the line, and whose length is equal to the distance traveled by the scanning beam in 10.2 microseconds, the duration of the combined blanking and synchronizing signal. The 20-second delay chosen for this illustration, it will be recalled, is approximately the delay produced as a result of a reflected signal traveling an additional 4 miles as illustrated in Fig. 1.

Whether the echo, as it appears upon the pic-

ture tube screen, will be a "dark" echo or a "light" echo, depends upon the phase relation between the video carrier and the echo carrier at the point of detection. If these carriers arrive more or less in phase, the resultant R. F. signal supplied to the detector will be greater than the amplitude of the video carrier alone, and, consequently, the combined signal will tend toward the black level and a "dark" echo will be produced as shown in line B. The darkest part of the echo will be that central portion which corresponds to the synchronizing pulse S_s , while the outer portions corresponding to the blanking signal S_b will be somewhat less dark, but darker than that part of the line which is not distorted by echo. On the other hand, if the video and echo carriers arrive in generally opposite phase, the reverse will be true, and a "light" echo such as that shown in line C will result.

Still a different type of echo results when television transmission is carried out in accordance with the system described by A. V. Loughren (Electronics, February 1940, pp. 27-30) or with the system described in the copending application of Frank J. Bingley, Serial No. 401,533, filed July 8, 1941. In the alternate carrier system disclosed by Bingley, the synchronizing pulse is transmitted not only as a variation in carrier amplitude (as in Fig. 2), but also as a variation or shift in carrier frequency. In this system, the synchronizing signal carrier may be of the order of 1 megacycle or more higher than the video signal carrier, and, consequently, when a reflected (and, hence, delayed) synchronizing signal is received with the video carrier, there will result a beat signal whose frequency is equal to the frequency difference between these signals, e. g., 1 megacycle. Since this frequency lies within the video frequency band, the synchronizing signal portion of the echo signal will be reproduced on the picture tube screen as an "alternating" echo, i. e., one which alternates from dark to light to dark, etc., as shown in line D of Fig. 2. The number of these light and dark bars depends upon the number of beat cycles contained within the duration of the synchronizing pulse. The change in shading from a dark bar to a light bar, and vice versa, is gradual, of course, and not abrupt, as shown in the illustration.

In general, where strong echo signals are received, the echo images reproduced upon the screen of the picture tube are apt to be more objectionable in an alternate carrier system than in the single carrier systems heretofore employed. This is because in the former system the synchronizing signal is transmitted at a frequency for which the receiver's sensitivity is approximately double that in the latter system, and, consequently, the reproduced echo is that much more pronounced.

Attention is now directed to Fig. 3 which illustrates one of the methods which may be employed, in accordance with the present invention, to effect substantial cancellation of echo patterns. No attempt has been made in this figure to maintain the identical scale employed in Fig. 2. Moreover, for simplicity, only the echo caused by the delayed arrival of the synchronizing signal is illustrated, the lesser echo produced by the blanking signal being omitted. The assumption in Fig. 3 is that transmission is carried out in accordance with the alternate-carrier system, i. e., where video and synchronizing signals are transmitted at substantially

different carrier frequencies, as described in the above-mentioned Bingley application.

Although it is customary in television practice to employ a raster, or scanning pattern, having 441 or more lines, interlaced, a description of the present invention is facilitated by reference to the 9-line interlaced rasters of Fig. 3. Frame No. 1 may be regarded as typical of all odd-numbered frames, and frame No. 2 as typical of all even-numbered frames. The order or sequence of scanning is indicated by the reference numerals 1 to 18 inclusive.

In an alternate carrier television system in which the video carrier differs substantially from the synchronizing carrier, say by one million cycles, an alternating echo-image will be produced on the television receiver's viewing screen similar to that already described with particular reference to line D of Fig. 2. Thus in line 1 of Fig. 3 the echo image is seen to consist of alternately dark and light line-segments, the number of alternations depending upon the number of beats which occur between the video and synchronizing carriers in the time taken for the scanning beam of the picture tube to trace or negotiate the distance between the left-hand side of the echo and the right-hand side thereof.

In accordance with the present invention, and in a manner to be described in detail hereinafter, it is proposed so to relate the frequencies of the video and synchronizing carriers that the "phase" of the alternating echo images will be displaced by substantially 180 degrees in successive lines. Thus in line 1 it will be noted that, scanning from left to right, the echo alternates according to the sequence: dark, light, dark, etc., whereas in line 2 (which, because we are dealing with an interlaced system, is actually the third line from the top) the alternating echo takes the sequence: light, dark, light, etc. It will also be observed that all odd numbered lines follow the sequence of line 1, while all even numbered lines follow the sequence of line 2. Now since we are dealing with a raster having an odd number of lines, to wit 9 in this illustration, it will be noted that the spacial sequence of odd- and even-numbered lines is reversed in frame No. 2 with respect to the order existing in frame No. 1. This is because the top line of the odd-numbered frames is an odd-numbered line, whereas the top line in the even-numbered frames is an even-numbered line. The effect of this is to produce alternating echo images in the even-numbered frames which are the reverse of the echoes in the odd-numbered frames. Described in another way, the alternating echoes in the even-numbered frames may be regarded as the complements or conjugates of the echoes in the odd-numbered frames.

Alternating echoes of the type illustrated in Fig. 3, consisting of three black segments and four white segments, or vice versa, are generally illustrative of the appearance of an echo produced by a television system in which the frequency difference between the video and synchronizing carrier is a large fraction of a megacycle. Obviously as the difference between the video and synchronizing carriers is decreased, the number of black and white echo segments will also be decreased. Where the frequency difference is small there may be only one or two black and white segments in the echo, and if the frequency difference is still less the echo in certain odd-numbered lines might be all black and the echo in certain even-numbered lines all white, or vice versa.

In any event, from the standpoint of the ob-

server, the optical effect produced by the rapid alternation of echoes of generally opposite characteristics upon the screen of the picture tube is substantially that which would obtain if no echoes were reproduced at all. In a conventional television system based on thirty complete frames per second, there will be fifteen complete "echo alternations" per second, each alternation consisting of one frame comparable to frame No. 1 of Fig. 3 and one frame comparable to frame No. 2 of that figure. Apparently the rapid substitution of light echoes for dark echoes, and vice versa, causes the eye to average the echo effects and to substantially ignore the individual echo images themselves. This is due to the optical effect known as the "persistence of vision."

According to the present invention the desired reversal of echo-image characteristics, from line to line and frame to frame, may be effected through the use of separate sources of video and synchronizing-signal carriers wherein the frequency of the synchronizing-signal carrier is made equal to the video carrier frequency plus an odd multiple of half the horizontal line frequency. Conversely the frequency of the video carrier might be made equal to the frequency of the synchronizing carrier plus an odd multiple of half the horizontal line frequency. More generally stated the requirement is that the difference in frequency between the video carrier and the synchronizing carrier be substantially an odd multiple of half the line frequency. As will be indicated at greater length hereinafter, echo cancellation will also obtain if the difference frequency is made an odd multiple of half the field frequency.

Reference is now made to Fig. 4 in which there is illustrated an alternate carrier television transmitter employing the present invention. With the exception of the apparatus designated with the reference numerals 33, 34, 35 and 36, the alternate carrier system shown therein has been fully described and illustrated in the above-named copending application of Frank J. Bingley.

Reference will first be made to the circuit of Fig. 4 without attention to the principles and added apparatus of the present invention. The rectangles 19 and 20 represent video carrier and synchronizing signal carrier generators respectively. The video generator 19 may consist of a master oscillator followed by one or more amplifiers or frequency multipliers. The synchronizing signal carrier generator 20 may consist of means, to be more fully described hereinafter, for generating a carrier which differs from that supplied by the generator 19 by a predetermined frequency. The vacuum tubes V₁ and V₂, which are supplied with signal from the generators 19 and 20 respectively, may be regarded as constituting an electronic switching device, responsive to a pair of control signals, for passing on to the amplifier and frequency-multiplier 22, a selected one of the carriers supplied by the devices 19 and 20. By means of the amplitude modulator 23 the signal derived from the device 22 may be modulated in accordance with the intelligence derived from the video, synchronizing, and blanking signal source 26. The modulator 23 may be followed by a suitable linear amplifier 24, which, in a single-side-band system, may be followed by a sesquio-side-band filter 25. Finally the signal may be supplied to a suitable antenna or radiator "A."

The electronic switching means, which include the tubes V₁ and V₂, may be controlled in response to a pair of control signals derived from

the source 26 as follows. By way of a conductor 37, a signal, comprising synchronizing signal components only, may be applied to a pair of networks 27 and 28. The network 27 is adapted to supply, in response to the applied synchronizing signal, a control signal which is highly negative with respect to the cathode of triode V₂ during the video and blanking intervals (exclusive of the synchronizing intervals), but only slightly negative during the synchronizing intervals themselves. Such signal is illustrated within the rectangle 27, the zero level being indicated by the line 0-0. Accordingly when this signal is applied to the grid of triode V₂ by way of the conductor 29 and the resistor 30, the triode V₂ is enabled to transfer the synchronizing carrier from source 26 to the stage 22 during the synchronizing intervals, but the triode is blocked during the longer video and blanking intervals by the application to its grid of the highly negative potential supplied by the device 27.

The network 28 supplies a control signal which, as is illustrated within the rectangle, is substantially the reverse of that supplied by the network 27. This signal, which is applied to the control grid of the triode V₁ by way of the lead 31 and the resistor 32, is only slightly negative during the longer video and blanking intervals, but is highly negative during the synchronizing intervals. As a result of the operation of the devices V₁, V₂, and 27, 28, there is provided a system wherein the video carrier is switched on during the video and blanking intervals, and off during the synchronizing intervals, while the synchronizing carrier is switched off during the video and blanking intervals, and on during the synchronizing intervals. Accordingly it will be seen that during the video and blanking intervals the modulator stage 23 amplitude modulates the video carrier with video and blanking signals derived from the source 26, while during the synchronizing intervals the modulator 23 amplitude modulates the synchronizing carrier with the synchronizing signals derived from the source 26.

Devices of the type represented by the rectangles 27 and 28 are well known in the art and require no detailed illustration.

In accordance with one embodiment of the invention it is contemplated that the carrier frequencies generated by the devices 19 and 20 be related in such a manner that the transmitted carriers, as radiated from the antenna "A," differ by an odd multiple of half the line frequency. Assume that it is desired to transmit a carrier frequency of 67,250,000 cycles per second during the video and blanking intervals, and that it is desired to transmit the synchronizing signals on a carrier having a frequency about one megacycle higher. Assume also that the projected system employs a raster of 525 lines, with 30 complete frames per second. Such a system has a line frequency of 15,750 cycles per second, whence half the line frequency is 7,875 cycles per second. An odd multiple of this half-line-frequency which will produce roughly the stated one million cycle difference-frequency is, for example, the number 125. The product of 125 and 7,875 is 964,375, i. e., roughly one megacycle. Consequently, the frequency of the synchronizing signal carrier will be substantially 67,250,000 plus 964,375, or 68,234,375 cycles per second.

If the frequency multiplier 22 is omitted, and its use is purely optional of course, the carrier generators 19 and 20 would be constructed and arranged to produce the video and synchronizing

carriers directly. If, however, a device 22 is employed which gives a frequency multiplication of, say, five times, the devices 19 and 20 should provide carriers of one-fifth of the carrier frequencies to be transmitted, which for the example presently under consideration would be 13,450,000 and 13,646,875 cycles respectively. The video carrier generator 19 may include a crystal controlled oscillator adjusted to oscillate at some pre-determined sub-multiple of the desired generator output frequency, in this example 13,450,000 cycles, followed by one or more frequency multiplier stages to bring the frequency up to the desired output frequency. The synchronizing carrier generator 20 may comprise any suitable device for generating a carrier which differs in frequency from the output of the generator 19, by the pre-determined, substantially constant difference frequency. Preferably the frequency difference is held constant by means of a positive tie-in, or interlock, between the two generators 19 and 20 in order to prevent drift or slippage as between the two systems. A satisfactory tie-in means is diagrammatically illustrated in Fig. 4. Since, in the example, the frequency difference between the carriers supplied by the generators 19 and 20 is 196,875 cycles, the 13,646,875 cycle carrier may be developed by first heterodyning the 13,450,000 cycle carrier with a signal having a frequency of 196,875 cycles, and then detecting the combined signal. The 196,875 cycle signal may be derived from the horizontal synchronizing signal in a manner presently to be described. The heterodyne detection of these two signals (13,450,000 cycles and 196,875 cycles) will, of course, produce a pair of new signals having frequencies equal respectively to the sum and difference of the frequencies of the heterodyned signals. The former, or sum-frequency signal, will have a frequency of 13,646,875 cycles, and since this is the frequency of the desired synchronizing signal carrier it may be selected, to the exclusion of the difference-frequency signal, and applied to the input circuit of the signal selector tube V₂.

Inasmuch as suitable heterodyne detection circuits are widely used in the art for a great variety of applications, it is not deemed necessary to illustrate the device 20 in detail in the present application.

It will be observed that the required 196,875 cycle signal has a frequency of 25 times one-half the line frequency. Consequently the 196,875 cycle signal may be obtained from the horizontal synchronizing signal source 26 as follows. The 15,750 cycle horizontal synchronizing signal may be applied to a frequency sub-multiplier or "halver" 33 to produce a new signal having a frequency of 7,875 cycles, i. e. of half the horizontal synchronizing frequency. Inasmuch as frequency halvers are well known in the art the device 33 is not illustrated in detail; however it may conveniently consist of a blocking tube oscillator adjusted to oscillate at approximately 7,875 cycles, and arranged to be fired by every second line synchronizing pulse supplied by the device 26. The 7,875 cycle signal from the frequency halver may be supplied to a suitable frequency multiplier 34 for multiplication up to the desired frequency, in the example here under consideration 196,875 cycles. In this case this is accomplished by means of a 25-fold multiplication. The 196,875 cycle output of the frequency multiplier 34, and the 13,450,000 signal from the device 19 may be applied to the heterodyne signal generator 20 by way of the paths 35 and 36 respectively.

With reference to Fig. 4 it is to be understood that the frequency values designated thereon are merely by way of example, and for the purpose of simplifying the description, and are not intended to limit the invention to any particular mode of operation.

In the foregoing it has been indicated that the frequency difference between the radiated video and synchronizing carriers should be equal to an odd multiple of half the picture line frequency. This is not a necessary restriction, since the frequency difference may also be defined as, or set equal to, an odd multiple of half the field frequency. In many, but not all, instances these definitions will be found equivalent. Thus for the example chosen in connection with the description of Fig. 4, the frequency difference between the two radiated carriers is also an odd multiple of half the frame frequency, specifically the 65,625th multiple of 15, where 15 is half the frame frequency. However, if the frequency difference between the two radiated carriers were only 15 cycles then it is obvious that the first-named definition would not apply.

That a system based on the second-named definition of carrier frequency difference produces the desired cancellation will be seen from the following consideration. Taking a 30-frame, 60-field system as an example, it will be seen that 30 a given point on a given line will be repeated each one-thirtieth of a second. For echo cancellation to obtain it will be sufficient that the carrier be, say, in phase with the echo at time $t + \frac{1}{30}$ and out of phase at time $t + \frac{2}{30}$, etc. Now if we establish 35 our video carrier at 60,000,000 cycles, and our synchronizing carrier at 60,000,030 cycles, there will be thirty beats per second as between the video carrier and the delayed synchronizing carrier, and each one-thirtieth second the phase of 40 the beat frequency (i. e., of the echo) will be the same. Under these conditions, of course, the echo will not cancel, since if in one frame a dark echo were produced, it would follow that in successive frames similar dark echoes would be produced. But if the video carrier is established at 45 60,000,000 cycles and the synchronizing carrier at 60,000,015 cycles, i. e., where the frequency difference is an odd multiple of half the frame frequency, echo cancellation will obtain because the phase of the beat frequency is reversed in successive frames. The same cancellation of the echo will obtain for carrier frequency differences of 45 cycles, 75 cycles, 105 cycles, etc.

It will be understood, of course, that where the difference frequency is so small that less than one beat cycle occurs for the duration of the echoed synchronizing pulse, an alternating echo of the type illustrated in line D of Fig. 2 will not obtain. In general, although the invention is not thus limited, it is preferred to have a relatively large difference in frequency between video and synchronizing carriers so that the full benefits of the alternate carrier method of television transmission may be secured.

It has been stated that echo cancellation may be effected by establishing separate video and synchronizing signal carriers whose frequencies differ by an odd multiple of half the line (or frame) frequency. An alternative specification of the requirements, and applicable generally to systems having an odd number of lines (as is conventional in interlaced systems), is that the frequency difference between the carriers shall be 75 such that the phase of the beats therebetween

shall undergo a change equal to an odd multiple of 180 degrees during each frame period.

So far the description has been directed more specifically to two-phase systems of echo cancellation. However, just as in the above-mentioned copending joint application of F. J. Bingley and Wm. E. Bradley, the present invention may also be employed in three-phase echo cancellation systems, or, in general, in systems wherein the differential phase between the video and synchronizing signal carriers changes at a rate such that echo images, which are reproduced on the screen of the picture tube at the receiving station, effectively cancel one another in a small number (e. g. two, three or four) of successive frames.

Whereas in a two-phase system the frequency difference between the carriers has been defined as an odd multiple of half the line (or frame) frequency, in a three-phase system the required frequency difference between carriers may be defined as an odd multiple of one-third the line (or frame) frequency. Preferably, in a three-phase system, and in order to avoid unnecessary complication of circuits, the total number of lines per frame is made equal to an odd number which is not divisible by three. Thus, a 605-line raster would be suitable for use in a three-phase echo cancellation system.

Although the present invention has been described and illustrated with reference to certain preferred embodiments, it should be understood that wide alterations and modifications may be effected within the scope of this invention as defined in the appended claims.

I claim:

1. In a television transmission system of the alternate carrier type, the method of minimizing the deleterious effects of echo signals on a desired signal, which comprises generating a first carrier wave, generating a second carrier wave, positively maintaining a substantially constant frequency difference between said carrier waves equal to an odd multiple of one n th the frame frequency, where n is an integer greater than one and smaller than four, utilizing the first of said waves for the transmission of video intelligence, and utilizing the second of said waves for the transmission of synchronizing intelligence.

2. In a television transmission system of the alternate carrier type, the method of minimizing the deleterious effects of echo signals on a desired signal, which comprises generating a first carrier wave, generating a second carrier wave, positively maintaining a substantially constant frequency difference between said carrier waves such that the differential carrier phase varies substantially uniformly at a predetermined rate so that the waves are in phase, as well as in antiphase, n times per second, where n is an odd multiple of half the frame frequency, utilizing the first of said waves for the transmission of video intelligence, and utilizing the second of said waves for the transmission of synchronizing intelligence.

3. In a television transmission system of the alternate carrier type employing an odd number of lines per frame, the method according to claim 2 wherein n is an odd multiple of half the line frequency.

4. In a television transmission system of the alternate carrier type, the method of minimizing the deleterious effects of echo signals on a desired signal, which comprises generating a signal having half the system's frame frequency, frequency-multiplying said signal by an odd factor, gen-

erating a first carrier wave of predetermined and substantially fixed frequency, heterodyning said frequency-multiplied signal with said first carrier wave to produce a second carrier wave differing in frequency from said first carrier wave by an amount equal to the frequency of said frequency-multiplied signal, utilizing one of said carrier waves for the transmission of video intelligence, and utilizing the other of said carrier waves for the transmission of synchronizing intelligence.

5. In an alternate carrier television system, the method according to claim 4, wherein the frequency of said frequency-multiplied signal is also an odd multiple of half the line frequency of the system.

6. In a television transmission system of the alternate carrier type, the method of minimizing the deleterious effects of echo signals on a desired signal, which comprises generating a signal whose frequency bears a fixed relation to the system's line frequency, generating a first carrier wave of predetermined and substantially fixed frequency, heterodyning said last-named signal with said first carrier wave to produce a second carrier wave differing in frequency from said first carrier wave by an amount equal to the frequency of said last-named signal, frequency-multiplying said first and second carrier waves to produce third and fourth carrier waves respectively so related in frequency that the carrier phase of echoes of the synchronizing signals changes with respect to the phase of the video signal carrier at a rate such that reproduced echo images effectively cancel one another in a small number of successive frames, utilizing one of the two last-mentioned carrier waves for the transmission of video intelligence, and utilizing the other of said waves for the transmission of synchronizing intelligence.

7. In an alternate carrier television system, the method according to claim 6, wherein the frequency difference between said third and fourth carrier waves is equal to an odd multiple of half the system's frame frequency.

8. In an alternate carrier television system, the method according to claim 6, wherein the frequency difference between said third and fourth carrier waves is equal to an odd multiple of half the system's line frequency.

9. In a carrier wave television transmission system of the alternate carrier type, the method of minimizing the deleterious effects of synchronizing signal echoes on the desired picture signals, which comprises continuously changing the phase of the synchronizing signal carrier relative to the phase of the video signal carrier to produce echo images of periodically varying and contrasting characteristics.

10. In a carrier wave television transmission system of the alternate carrier type, the method of minimizing the deleterious effects of synchronizing signal echoes on picture signals, which comprises progressively varying the phase between the video signal carrier and the synchronizing signal carrier to effect reversals, in predetermined time sequence, of the differential carrier phase between horizontal synchronizing signals and the succeeding line signals.

11. In an alternate carrier television transmission system, the method of minimizing the deleterious effects of echo signals on a desired signal, which comprises generating a video signal carrier of substantially fixed frequency, generating a synchronizing signal carrier whose frequency is substantially equal to the frequency of

the video signal carrier plus an odd multiple of half the horizontal line frequency, and modulating said carriers respectively with the video and synchronizing signals.

12. The method according to claim 11, wherein the frequency-difference between the carriers is of the order of a million cycles.

13. In a television transmitter of the alternate carrier type, a source of video and synchronizing signals, means for generating a first carrier wave of predetermined frequency, means for generating a second carrier wave of different frequency, means for establishing and maintaining a substantially fixed frequency-difference between said carrier waves substantially equal to an odd multiple of half the horizontal line synchronizing frequency, means for modulating one of said carrier waves with said synchronizing signals, means for modulating the other of said carrier waves with said video signals, means for transmitting said one carrier wave during the synchronizing signal intervals, and means for transmitting said other carrier wave during the video signal intervals.

14. In a television transmitter of the alternate carrier type, a source of video and synchronizing signals, means for generating a first carrier wave of predetermined frequency, means for generating a second carrier wave of different frequency, means for establishing and maintaining a substantially fixed frequency-difference between said carrier waves substantially equal to an odd multiple of half the frame frequency, means for modulating one of said carrier waves with said synchronizing signals, means for modulating the other of said carrier waves with said video signals, means for transmitting said one carrier wave during the synchronizing signal intervals, and means for transmitting said other carrier wave during the video signal intervals.

15. A television transmitter of the alternate carrier type as claimed in claim 13, wherein the frequency-difference between said carrier waves is of the order of a million cycles.

16. In a television transmitter of the alternate carrier type, a source of video and synchronizing signals, means for generating a first carrier wave of predetermined frequency, means for generating a second carrier wave of different frequency, means for establishing and maintaining a substantially fixed frequency-difference between said carrier waves substantially equal to an odd multiple of half the horizontal line synchronizing frequency, wave selector means responsive to a control signal for selecting said carrier waves in predetermined alternating sequence, and means for amplitude-modulating the selected carrier wave in accordance with signals from said video and synchronizing signal source.

17. A television transmitter of the alternate carrier type as claimed in claim 16, including means for generating a control signal adapted to effect selection of one of said carrier waves during the synchronizing signal intervals and selection of the other carrier wave during the video signal intervals.

18. In a television transmitting system of the alternate carrier type, a source of video signals, a source of line synchronizing signals, means responsive to signals from said last-named source for generating a signal of half the line frequency, means responsive to said half-frequency signals for generating a signal whose frequency is an odd multiple of said half-frequency, means for generating a first carrier wave of predetermined fre-

quency, heterodyne means for mixing said first carrier wave with said last-named signal to produce sum and difference signals, means for utilizing one of said last-named signals as a second carrier wave, means for modulating one of said carrier waves with said synchronizing signals, means for modulating the other of said carrier waves with said video signals, means for transmitting said one carrier wave during the synchronizing signal intervals, and means for transmitting said other carrier wave during the video signal intervals.

19. In a television transmission system of the alternate carrier type, means for generating a video signal carrier of predetermined frequency, and means for generating a synchronizing signal carrier of different predetermined frequency so related numerically to the frequency of the video signal carrier that the carrier phase of echoes of the synchronizing signals changes with respect to the phase of the video signal carrier at a predetermined rate to effect mutual cancellation of reproduced echo images in a small number of successive frames.

20. In a television transmission system of the alternate carrier type, means for generating a video signal carrier of predetermined frequency, and means for generating a synchronizing signal carrier of different predetermined frequency so related numerically to the frequency of the video signal carrier that the carrier phase of echoes of the synchronizing signals changes with respect to the phase of the video signal carrier at a predetermined rate to impart substantially opposite characteristics to reproduced echo images in consecutive frames, whereby said echo images effectively cancel one another.

21. In a television transmission system of the alternate carrier type, means for generating a video signal carrier of predetermined frequency, and means for generating a synchronizing signal carrier of different predetermined frequency so related numerically to the frequency of the video signal carrier that the phase of beats between the two carriers is reversed in consecutive frames, whereby reproduced echo images are caused effectively to cancel one another.

22. In a television transmission system of the alternate carrier type employing an odd number of lines per frame, means for generating a video signal carrier of predetermined frequency, and means for generating a synchronizing signal carrier of different predetermined frequency so related numerically to the frequency of the video signal carrier that the phase of beats between the two carriers changes during each frame period by an amount equal to an odd multiple of 180 degrees, whereby reproduced echo images are caused effectively to cancel one another.

23. In a television transmission system, the method of minimizing the deleterious effects of a first carrier wave on a second carrier wave, which comprises establishing and maintaining a substantially constant frequency difference between said carrier waves equal to an odd multiple of one-nth the frame frequency, where n is an integer greater than one and smaller than four.

24. In a television transmission system, means for generating a first carrier wave, means for generating a second carrier wave, and means for establishing and positively maintaining a substantially constant frequency difference between said carrier waves equal to an odd multiple of one-nth the frame frequency, where n is an integer greater than one and less than four.

25. In a television transmission system of the alternate carrier type, means for generating a first carrier wave, means for generating a second carrier wave, means for positively maintaining a substantially constant frequency difference between said carrier waves such that the differential carrier phase varies substantially uniformly at a predetermined rate so that the waves are in phase, as well as in antiphase, n times per second, where n is an odd multiple of half the frame frequency, means for utilizing said first carrier wave for the transmission of video intelligence, and means for utilizing said second carrier wave for the transmission of synchronizing intelligence.

26. In a television transmission system of the type employing an odd number of lines per frame, means for generating a first carrier wave, means for generating a second carrier wave, and means for establishing and positively maintaining a substantially constant frequency difference between said carrier waves such that the differential carrier phase varies substantially uniformly at a predetermined rate so that the waves are in phase, as well as in antiphase, n times per sec-

ond, where n is an odd multiple of half the line frequency.

27. In an alternate carrier television transmission system, means for generating a video signal carrier of substantially fixed frequency, means for generating a synchronizing signal carrier whose frequency is substantially equal to the frequency of the video signal carrier plus an odd multiple of half the horizontal line frequency, and means for modulating said carriers respectively with the video and synchronizing signals.

28. In an alternate carrier television transmission system, means for generating a video signal carrier of substantially fixed frequency, means for generating a synchronizing signal carrier whose frequency differs from that of the video signal carrier by approximately a million cycles, and is substantially equal to the frequency of the video signal carrier plus an odd multiple of half the horizontal line frequency, and means for modulating said carriers respectively with the video and synchronizing signals.

FRANK J. BINGLEY.
